UNITED STATES PATENT OFFICE.

WILLIAM A. JOHNSTON, OF JERSEY CITY, NEW JERSEY.

MAIL-BAG.

SPECIFICATION forming part of Letters Patent No. 469,028, dated February 16, 1892.

Application filed October 2, 1891. Serial No. 407,537. (No model.)

To all whom it may concern:

Be it known that I, WILLIAM A. JOHNSTON, a citizen of the United States, residing at Jersey City, in the county of Hudson and State 5 of New Jersey, have invented certain new and useful Improvements in Mail-Bags; and I do hereby declare that the following is a full, clear, and exact description of the same, reference being had to the annexed drawings, 10 making a part of this specification, and to the letters of reference marked thereon.

This invention relates to certain new and useful improvements in mail-bags; and it has for its objects, among others, to provide an improved mail bag or sack which shall have a flexible mouth or mail-receiving opening and which, when closed, shall be rigid at the mouth and will be a safeguard against tampering with the contents of the bag or sack. I provide 15 the mouth of the bag and the flap with metallic plates which, when the bag is closed, overlap to prevent bending of the sides of the mouth for the purpose of removing the locking means, but which are so arranged that when 20 the mouth of the bag is opened they will permit of sufficient flexibility thereof for all the required purposes. I line the inner faces of the locking-tongues with metal to prevent bending thereof to unlock the bag. 25 Other objects and advantages of the invention will hereinafter appear, and the novel features thereof will be specifically defined by the appended claims.

The invention is clearly illustrated in the 30 accompanying drawings, which, with the letters of reference marked thereon, form a part of this specification, and in which—

Figure 1 is a side elevation of the mouth portion of the bag with the parts in their 35 locked position. Fig. 2 is a side elevation of the mouth portion of the bag with the flap thrown open. Fig. 3 is a cross-section on the line $z-z$ of Fig. 1.

Like letters of reference indicate like parts 40 throughout the several views.

Referring now to the details of the drawings by letter, A designates a portion of a mail-bag of known construction except at the mouth end, and therefore only the upper portion 45 has been shown. It is provided with a flap B, to the inner face of which are secured in

any suitable manner the metallic plates C, which, instead of being one rigid strip, are separated, as seen best in Fig. 2, for a purpose hereinafter made apparent. These strips are 55 provided with the staples D, with which the locking-tongues are designed to engage in a manner hereinafter explained. Around the upper end of the bag is a strengthening-strip E, which is provided upon opposite sides of 60 the mouth with the slits or openings a for the reception of the staples D.

F are metallic plates secured to this strengthening-strip and arranged to alternate with the metallic plates or strips upon the 65 flap when the mouth of the bag is closed, as seen in Fig. 3. Suitable openings or slits b are made in these plates to coincide with those in the opposite sides of the bag, as seen in Fig. 3. 70

G is the locking-bar of a flexible material, as leather, provided with the tongues c and with longitudinal slots d, which are adapted to receive the guide-pins e on the bag, as seen best in Fig. 1, this manner of locking the 75 mouth of the bag being of the usual construction and form. The inner faces of these tongues are faced with metal, as seen at f, for two reasons, to prevent wear thereon as the locking-bar is moved back and forth and to 80 prevent bending of the tongues by malicious persons to unlock the bag. The central tongue through which the locking-staple H passes is faced with metal upon both sides, as seen in Fig. 3. 85

I is the locking-hasp hinged to the locking-bar, as seen in Figs. 1 and 3, and provided with a slot for the passage of the locking staple, as seen in said figures. It is formed with a depression or bend, as seen in Fig. 3, for 90 the reception of the staple thereunder.

In operation when the bag is locked the metallic plates or strips on the flap and face of the bag overlap each other, as seen in Fig. 3, and thus provide a rigid unbendable 95 mouth, and the metallic lining to the tongues prevent them being bent to disengage them from their staples, as may be done when not thus lined. When the locking-bar is moved to disengage its tongues from the staples the 100 mouth of the bag may be opened, the separated metallic plates permitting of the neces-

sary flexibility at the mouth, as will be readily understood. The alternating arrangement of the metallic plates is important, for if they were not thus arranged there would 5 still be considerable flexibility at the mouth when the bag was locked. By my construction the mouth of the bag, when closed, is as stiff and rigid as if provided with a single rigid bar extending entirely across the bag.

10. What I claim as new is—

1. A mail-bag having its mouth and flap provided with separated metallic plates alternately arranged to overlap when the mouth of the bag is closed and a locking-bar of 15 flexible material having tongues lined with metal, substantially as specified.

2. A mail-bag having its flap and mouth

provided with alternately-arranged separated metallic plates having slots for the staples, said plates arranged to overlap when the bag is closed, a sliding locking-bar of flexible material provided with metal-faced tongues, and a locking-hasp hinged to one of the tongues of the locking-bar and having a bend near its hinge end to receive the staple, substantially 25 as and for the purpose specified.

In testimony that I claim the above I have hereunto subscribed my name in the presence of two witnesses.

WILLIAM A. JOHNSTON.
